UNITED STATES PATENT OFFICE.

JOSEPH SOSS, OF BROOKLYN, NEW YORK.

INVISIBLE HINGE.

Application filed July 20, 1926. Serial No. 123,767.

This invention relates to invisible hinges and particularly to hinges of this class employing sheet metal butt members of similar form and construction movably coupled together by two or more link members pivoted to the respective butts and movable relatively thereto; and the object of the invention is to provide a hinge of the class specified, the separate butts of which may be fashioned 5 from a strip of sheet metal of substantially the same dimensions throughout its length and the strip so folded as to form a U-shaped butt body having oppositely disposed flanges at the ends of the side members of said U-shaped body; a further object being to so fashion the side members and crosshead of the body as to fit snugly within a circular or otherwise formed recess or aperture in a stationary or swinging member or in both, 10 and to be retained against displacement from said member; and with these and other objects in view, the invention consists in a hinge of the class and for the purpose specified which is simple in construction, efficient in 15 use, and which is constructed as hereinafter described and claimed.

The invention is fully disclosed in the following specification, of which the accompanying drawing forms a part, in which the 20 separate parts of my improvement are designated by suitable reference characters in each of the views, and in which:—

Fig. 1 is a face view of a stationary support and swinging member with my improved hinge mounted in connection therewith, with the door in open position and part of the construction being broken away.

Fig. 2 is a partial section on the line 2—2 of Fig. 1.

Fig. 3 is a partial section on the line 3—3 of Fig. 1.

Fig. 4 is a section on the line 4—4 of Fig. 3.

Fig. 5 is a plan view of a blank from which one of the butts shown in Figs. 1 to 4 inclusive is formed.

Fig. 6 is a plan view of a part of a blank showing a slight modification; and,

Fig. 7 is a detail sectional view of the hinge butt detached, similar to that seen in Fig. 4 but showing a modification.

In the drawing, I have indicated at 10 and 11 the stationary support and swinging member having cylindrical sockets or recesses 10^a and 11^a to receive the separate butts 12—12^a of my improved hinge construction. The butts 12 and 12^a are both of similar construc-

tion and one of these butts will be described specifically, the reference numerals applying to both butts. Each of the hinge butts is fashioned from a sheet metal blank as seen in Fig. 5 of the drawing comprising a central crosshead portion 13 which constitutes the inner end of the butt, two similar side portions 14 foldable into parallel relation and at right angles to the crosshead 13 on the lines 15 to bring the arc-shaped grooves 16 on the separate side portions 14 on adjacent faces of said side portions to produce a substantially U-shaped butt body, and the parts 14 form spaced bearings for the links 17 and 18 employed for coupling the separate butts together.

The grooves 16 are formed by depressions in the parts 14 of the blank and said grooves open outwardly through one side of the parts 14 adjacent the crosshead 13 as seen at 19 to permit of the passage of the pins 20 carried on the ends of the links 17 and 18 into the respective butt members. The pins 20 operate in the grooves 16, which serve to guide 80 and reinforce said link members in their movement.

The ends of the parts 14 have flanges 21 foldable on the lines 22 at right angles to the parts 14 and in opposite directions. The flanges in the construction shown in Figs. 1 to 5 inclusive are semi-circular in form and are adapted to fit within the cylindrical recesses 10^a and 11^a and to lie flushly with the outer faces of the stationary support 10 and 90 swinging member 11 as clearly illustrated in Figs. 2 and 3 of the drawing. The flanges 21 serve to close the spaces 23 formed at the opposite sides of the parts or bearings 14 of the respective butts so that when the separate butts are mounted in position, the chambers 24 between the parts 14 only are exposed, and the links 17 and 18 operate in said chambers which open outwardly 95 through the stationary support and swinging member.

The links 17 and 18 are pivoted together as seen at 25 and the link 17 is pivoted to a pivot pin 26 mounted in apertures 27 in the butt 12. The apertures 27 are arranged in 105 opposite relation on the separate parts 14 as will be apparent. The link 18 is similarly mounted on a pin 28 mounted in the apertures 27 of the butt 12^a as clearly seen in Fig. 3 of the drawing.

The inner end or crosshead 13 of the separate butts is provided with projecting prongs

29 fashioned from the material of said cross-head and which project in common alignment with the bearing portions 14 of the butts and are preferably flared outwardly as seen at 30 in Fig. 2 of the drawing so that in driving the separate butts into position, the flared prongs will serve to hold the butts against displacement from the stationary support and swinging member. The outer 10 side edges of the parts 14 are also preferably sharpened by beveling or otherwise, as seen at 31 to engage the walls of the recesses 10^a—11^a to fixedly retain the bearing members 14 in spaced relation and also to aid in securing the separate butts in position. It 15 will be understood that this contact or engagement will be very slight however, and the showing in the drawing is exaggerated to clearly illustrate the feature in question.

20 My present invention is an improvement on that shown and described in two prior applications, Serial No. 71,539 filed November 27, 1925, and Serial No. 91,400 filed March 1, 1926. The distinctive features of 25 the present invention reside in the fashioning of the hinge butts from a strip of sheet metal of substantially the same dimensions throughout its length without any projecting parts or butts, which result is accomplished by coupling the bearing plates or 30 member 14 by a crosshead 13 at the inner end of the butt rather than by a member disposed at the sides of the bearing members as in the earlier applications. This feature 35 not only simplifies the production but materially reduces the manufacturing costs, especially in the elimination of waste material.

By virtue of the present construction, a 40 hinge of the class under consideration may be produced at a considerably less cost than the devices covered by the earlier applications. With the present construction, I also provide means for rigidly retaining the bearing portions 14 on the respective butts in the socket provided in the stationary support and swinging member. This operates 45 to reinforce said bearing members and to retain them in proper spaced relation, which result is also accomplished by the crosshead 50 13 and the flanges 21.

55 In Fig. 6 of the drawing, I have shown a slight modification in which I have substituted for the arc-shaped or semi-circular flanges 21, straight flanges 32 to adapt the hinge butts to apertures or recesses of square or oblong form rather than cylindrical form as shown in Figs. 1 and 4 of the drawing, it being understood that my invention is not necessarily restricted to the use of my hinge 60 in connection with sockets of any particular cross sectional form, the separate butts being fashioned to suit the desired requirements in this respect. While I have shown

certain details of construction for carrying my invention into effect, it will be apparent 65 that I am not necessarily limited to these details, and various changes in and modifications of the construction herein shown and described may be made within the scope of the appended claims without departing from 70 the spirit of my invention or sacrificing its advantages.

In Fig. 7 of the drawing, I have shown a sectional view of the hinge detached, the section being similar to that shown in Fig. 4 75 of the drawing except that a slight modification is shown, which consists in providing flange extensions 33 and 34 at one side of the bearing members 14, preferably the side adjacent the pivot pin apertures 27. The 80 flanges 33 and 34 are of such width that when the bearing members 14 are arranged in parallel relation, said flanges will abut one against the other to retain the bearing members 14 in spaced relation when mounted in 85 the socket of a suitable support. It will also be apparent that the flanges 33 and 34 will serve to reinforce the side of the hinge butt in connection with which the links of 90 the hinge are pivoted.

Having fully described my invention, what I claim as new and desire to secure by Letters Patent, is:—

1. A hinge butt for mounting in a cylindrical socket in a support, comprising a substantially U-shaped sheet metal body, the crosshead of said body constituting the inner end of the butt, the side members of said butt forming the bearings of the butt, the outer ends of said side members having laterally 100 extending flanges, the edges of said flanges being arc-shaped in form to fit within said cylindrical socket, and the side edges of said bearing members engaging the walls of the socket in mounting the butt therein. 105

2. A hinge butt for mounting in a cylindrical socket in a support, comprising a substantially U-shaped sheet metal body, the crosshead of said body constituting the inner end of the butt, the side members of said butt forming the bearings of the butt, the outer ends of said side members having laterally 110 extending flanges, the edges of said flanges being arc-shaped in form to fit within said cylindrical socket, the side edges of said bearing members engaging the walls of the socket in mounting the butt therein, and means integral with the inner end of the butt for engaging the inner wall of the socket for securing the butt against displacement therefrom. 115 120

In testimony that I claim the foregoing as my invention I have signed my name this 14th day of July, 1926.

JOSEPH SOSS.
